UNITED STATES PATENT OFFICE.

ROBERT F. PADEN, OF GLENDALE, MISSOURI.

SAFETY DEVICE.

Application filed October 19, 1925. Serial No. 63,387.

This invention relates to safety devices, and more particularly to a guard for preventing injury to an operator by the rotating cutter of a woodworking machine or other machines of similar character. It has for its objects to produce a relatively simple, efficient and practical device for the above noted purpose, which is readily applied to the machine without material alteration thereof or in the least interfering with its regular operation or the manipulation of the work thereon; to improve generally upon devices of its character; and to attain certain advantages as will more fully appear in the following description.

The invention consists in the novel construction and operation of a guard normally surrounding the cutter in proximity to the work-table or support, but being liftable and automatically operated by the work pressing against it when moving in any direction on the table or support. It further consists in the parts and combinations and arrangements of parts hereinafter described and afterwards pointed out with particularity in the appended claims.

In the accompanying drawings forming part of this specification and illustrating a practical adaptation of the invention:—

Figure 1 is a view partly in side elevation and partly in vertical section, showing the device as applied to the machine and the parts in normal position;

Figure 2 is a top plan view of the horizontal hanger arm detached from the supporting standard;

Figure 3 is a detail view of the retaining plate detached from said hanger arm;

Figure 4 is a top plan view of the hand-wheel for effecting the adjustment of the hanger arm on the supporting standard;

Figure 5 is an end view of the bushing on which the hand-wheel is adjusted;

Figure 6 is a section on the line 6—6 of Figure 1;

Figure 7 is a section on the line 7—7 of Figure 1;

Figure 8 is a detail view of the guard-elevating nut and the bushing or plug which co-operates therewith; and

Figure 9 is an end view of said bushing or plug.

Referring now to the drawings, the numeral 1 designates the work-table of an ordinary woodworking machine commonly known as a "shaper." Operating through

an opening 2 in the table 1 is a vertical shaft or spindle 3 having the usual cutter 4 fastened thereon.

On the table 1 is a bracket or base member 5, extending upward from which is a post or supporting standard 6. The upper end portion of the post 6 is grooved longitudinally, as at 7, and sleeved on the post, with a key or spline 8 slidably fitted in said groove 7, is a horizontal hanger arm 9. This arm is secured in its adjusted position by a set-screw 10, and co-operating with said arm is a hand-wheel 11 whose hub portion 12 is internally screw-threaded to fit on the externally screw-threaded portion of a bushing 13 which is sleeved on the post 6. Said bushing 13 is provided with a key or spline 14 slidably fitted in the groove 7, and it is fastened in its adjusted position on the post 6 by a set-screw 15.

Suspended from the horizontal hanger arm 9 is a tube 16. This tube is provided with a head 17 in its upper end portion, said head having an upwardly extending axial neck or shank 18 on the end of which is an annular flange or enlargement 19. This enlargement 19 is fitted somewhat loosely in a circular recess 20 provided therefore in the hanger arm 9, said arm being provided with a slot 21 wide enough to permit the enlargement 19 to pass freely therethrough, and said slot 21 being connected with an axial opening 22 at the bottom of said recess 20 by a narrower slot 23 which is of a width substantially the same as the diameter of said opening 22 and permits the neck or shank portion 18 to pass freely therethrough. By this arrangement, the neck or shank portion 18 is movable longitudinally through the wider slot 21 from the under side of said arm 9 until the enlargement 19 clears the upper side of said arm 9, after which the neck or shank 18 is readily passed transversely through the narrower slot 23 until said enlargement 19 is in position to enter said recess 20.

Interposed between the bottom of said recess 20 and said enlargement 19 is a washer 24 of rubber or some suitable felted or fibrous mass possessing a certain amount of resiliency, while on top of said enlargement 19 is a disk 25 of material similar in character to said washer 24, the disk 25 being covered by a retaining plate or disk 26, which, as shown, is a circular disk and releasably secured in place by screws 27. By this arrangement

angement, the tube 16 is normally suspended vertically from the arm 9, yet it is capable of swinging movement when pressure is brought to bear laterally upon it, and to 5 permit this swinging movement, within certain limitations as will later be described, the wall of the opening 22 is downwardly flared, as at 28 (see Figure 1).

Sleeved on the tube 16 is a collar 29, and 10 to afford an easy movement of the latter on the tube, as will be more fully set forth later on, antifriction bearings 30 are preferably interposed between said members. Secured on the collar 29, as by screws 31, is an annular housing or cage 32 which normally surrounds the cutter 4 and rests upon or has its lower edge in close proximity to the work-table 1. This housing, which constitutes the guard proper for the cutter, may comprise a top wall 33 with a plain cylindrical flange, but it is preferable to provide said flange with a multiplicity of apertures of sufficient size to permit a view of the cutter yet small enough to prevent the operator's 15 fingers from passing therethrough. Preferably, these apertures are vertical slots 34, and, obviously, the same effect may be had by constructing the guard flange of a multiplicity of rods or bars in cage-like arrangement.

In practice, the guard housing or cage 20 may be made in different sizes to accommodate cutters of various forms and sizes, and they may be obviously interchangeably 25 mounted on the collar 29 by having an uniform arrangement of the securing screws 31 for the attachment of all sizes.

Secured in the upper portion of the tube 16 is a cross-head or support 35 in the center 30 of which is an antifriction bearing 36. Supported axially from the inner ring 37 of said bearing is a shaft 38. This shaft, as shown, has a reduced upper end portion 39 affording a shoulder to engage the under side of 35 said bearing ring 37, and it is further reduced in diameter and screw-threaded, as at 40, to receive a clamping nut 41.

The shaft 38 is provided throughout the major portion of its length with screw- 40 threads 42 of relatively long pitch, and working on said threaded portion is a cylindrical nut 43 having an annular flange 44 at its lower end. This nut 43 is located in a cylindrical box 45 having an axial opening 45 in its top wall 46 through which said nut is freely slidable, while said flange portion 44 of the nut is slidably fitted to the interior face of said box. On the under face of the flange portion 44 is an annular series of serrations 47 which co-operate with a counterpart series of serrations 48 on the upper face of a bushing ring 49, which latter is screw-threaded into the lower end portion of said box or otherwise secured therein to afford an 50 abutment for said nut. The nut is nor-

mally held in engagement with said member 49 by a spring 50 which is interposed between the top wall 46 of the box and said flange 44 of the nut and being under sufficient tension so that, under normal conditions, the interlocking of the serrations 47 and 48 holds the nut from rotation in said box, and whereby, when said shaft 38 is rotated, the nut is caused to move lengthwise on its screw-threaded portion 42.

The box 45 has an annular flange 51 at its lower end which is provided with a series of arcuate notches 52. Slidably secured to the under side of said flange 51 is an annular member or ring 53, said member being supported by segmental plates or disks 54 which span said notches 52 and are apertured for the reception of screws or bolts 55 which enter said member 53 and by which arrangement there is limited relative movement between said box 45 and said member 53. The member 53 is provided with two diametrically disposed arms or extensions 56 having angular end portions which are secured to the collar 29 by screws 57, said arms or extensions 56 being projected through longitudinal slots 58 in said tube 16 so as to permit said collar 29 to move lengthwise of said tube, yet being held from rotation thereon.

A clutch member 59 having a screw-threaded stem or shank 60 which is threaded reversely to the threading 42 of the shaft 38 is secured axially in the end of the shaft or spindle 3 of the cutter 4. This clutch member 59 is provided with an antifriction bearing 61 in the inner ring member of which the lower end portion of the shaft 38 is fitted slidably and laterally supported. A co-operating clutch member 62 having a central hub portion 63 is slidably mounted on said shaft 38 as by a slot-and-pin connection whereby independent rotation of the member 62 is prevented but it is permitted movement longitudinally on the shaft. That is to say, said hub portion 63 is provided with two diametrically opposed longitudinal slots 64 through which the ends of a cross-pin 65 in the shaft 38 projects. Interposed between said cross-pin 65 and an annular shoulder afforded by a tapered head 66 on the upper end of said hub portion 63 is a spring 67 which is somewhat weaker than the hereinbefore described spring 50, the function of said spring 67 being merely to yieldably hold said clutch member 62 disengaged from said clutch member 59, while the spring 50 must be strong enough to normally support the combined weight of the box 45, ring member 53, collar 29, guard housing 32 and the associated parts therewith.

Fixed on the shaft 38, as by a pin 68, is an abutment member 69 having an inverted tapered head 70 in opposed relation to the

head 66 on the hub portion of the clutch member 62 and against which said clutch member 62 is normally held by said spring 67. Supported between the said two heads 5 66 and 70 is an annular wedge element 71 which is of external diameter a little less than the diameter of an opening 72 in the center of a cross-head or support 73 which is secured in the lower portion of said tube 10 16.

The operation of the device will now be described.

A guard housing 32 of the proper size according to the cutter being used on the machine having been selected and mounted on the collar 29, and the clutch member 59 having been secured in the end of the cutter shaft or spindle 3, the arm 9 is then adjusted to the proper height on the post or 15 supporting standard 6, so that the clutch member 62 is clear of engagement with the clutch member 59 as shown in Figure 1. This adjustment is readily effected by loosening the set-screw 10 and setting the arm 20 9 as accurately as possible and then tightening the set-screw. The bushing sleeve 13 with the hand-wheel 11 thereon is then adjusted with relation to said arm 9, and if the latter needs further adjustment the set-screw 10 may be loosened and the hand-wheel 11 moved up or down, as the case may be, on said bushing sleeve 13 so that the arm 25 9 is accordingly raised or lowered and the final adjustment effected to the minutest 30 degree.

Preferably, the guard housing 32 rests on the work-table 1, but, if desired, in some cases, it may be suspended just a slight distance clear of the table by proportioning the 35 slots 58 in the tube 16 so that when said tube is at the proper elevation to have the clutch members 59 and 62 normally disengaged the arms or extensions 56 of the member 53 rest at the lower ends of said 40 slots 58 and the marginal portion of the guard housing is clear of the table.

Obviously, the shaft 38 is normally idle owing to the disengagement of the two clutch members 59 and 62. However, when 45 the work is moved on the table 1 and pressed against the guard housing 32 the tube 16 is swung accordingly on its supporting head 19, the slidible coinnection between said box 45 and ring member 53 afforded by the arrangement of the notches 52, supporting plates or disks 54 and screws or bolts 55 permitting this.

As the tube 16 swings thus, the wedge ring 50 71 is forced between the two heads 66 and 70, and the head 70 being stationary on the shaft 38 the clutch member 62 is moved downward against the tension of the spring 67 and into engagement with the clutch member 59, whereupon said shaft 38 is 55 caused to rotate with the shaft or spindle 3.

Assuming that said shaft or spindle 3 is rotating counter clockwise, looking at the cutter from above, and the screw-thread 42 on said shaft 38 being a left-hand thread as shown in the drawings, the nut 43 which 70 is normally held from rotation in said box 45 is caused to travel upward on said shaft 38, for the reason that, while there is limited sliding movement between said box and said ring member 53, any rotative movement 75 of said box 45 about said shaft 38 is arrested as soon as the walls of the notches 52 engage said screws or bolts 55. As said nut 43 travels upward the box 45, supported by 80 said spring 50, moves upward with it, and the guard housing 32, of course, is accordingly elevated. This upward travel of the parts continues until the work slides under said guard housing and as soon as lateral pressure is released from said guard housing 85 the pressure of the wedge ring 71 is released from the head of said clutch member 62 and the spring 67 disengages the clutch member 62 from said clutch member 59, whereupon the shaft 38 ceases to rotate under the power 90 of said shaft 3, and it being freely supported in its antifriction bearings 36 and 61 it is rotated in the opposite direction by the action of the nut 43 on the threads 42 there- 95 of as the guard housing 32, augmented by the combined weight of the connected parts between it and said box 45, drops upon the work and back to normal position about the cutter as soon as the work is withdrawn 100 from under said guard housing.

In machines of the character on which the present invention is primarily designed to be used the cutters rotate at a very high rate of speed, yet under the ordinary conditions the device has been found to operate ideally. 105 However, if the work is unusually rough so as to create an undue amount of frictional engagement with the edge of the guard housing 32 while passing thereunder and thereby tend to continually keep the clutch members 59 and 62 engaged or should any condition exist so as to cause the housing to continue moving upward after the work is thereunder a cushioned stop device may be employed. To this end a split ring member 74 (see 110 Figures 1 and 6) may be clamped about the tube 16 in different adjusted positions, said ring member being provided with apertured ears 75, 76 at its ends for the reception of a clamping bolt 77. This ring member may have two or more vertically apertured lugs 78 through which are slidably fitted spring-pressed bars 79, the springs 80 being interposed between the under sides of said lugs 115 and heads 81 at the lower ends of said bars. 120

In practice, the thickness of the work to be operated upon having been determined, the ring member 74 is adjusted on said tube 16 so that the under faces of the heads 81 125 of the bars 79 are in a plane just slightly 130

above that where the upper faces of the extensions 56 or the upper end of the sleeve 29, as the case may be, reach when the guard housing has been elevated sufficiently to allow the work to pass thereunder. Therefore, should the housing continue to move upward beyond the predetermined plane, it will be arrested by said members 79 with cushioning effect, however, due to the provision of the springs 80, and, as may be here stated, said springs 80 being considerably stronger than said spring 50, the latter will yield under the resistance of the former, whereby the serrations 47 of the nut 43 will ride out of their seated engagement in the serrations 48 of the member 49 so that said nut is free to rotate with said screw-threaded portion of the shaft 38 within the box 45 and without further endwise movement during such disengagement of said serrated portions.

Furthermore, should the operator press the work against the guard housing 32 with excess force or should anything happen to hold the guard housing or the connecting parts between it and said nut 43 from rising with said nut during the forceful rotation of said shaft 38, the spring 50 will yield just as above described in connection with the functioning of the said cushion safety stop.

It is noted that while the tube 16 is capable of swinging on its supporting head 19 in the operation of the device as herein described, the shaft 38 is at all times maintained in substantially true axial alignment with the shaft or sprindle 3, as said shaft is supported at its upper end relatively near said supporting head 19 and is thrown but slightly out of its normal position. Said shaft therefore rotates with substantially no appreciable wobble during the operation of the device.

Obviously the device admits of considerable modification without departing from the spirit and scope of the invention as defined by the appended claims. Therefore, it is not limited to the specific construction and arrangement shown in the drawings.

What is claimed is:

1. In a guard of the character described, a housing normally surrounding the cutter, said housing being capable of vertical movement and limited lateral movement, and means for raising said housing including a normally inactive screw-shaft axially aligned with the axis of the cutter, a clutch member rotating continuously with said cutter, a cooperative clutch member on said screw-shaft, and an actuator element correlated to one of said clutch members for effecting the engagement of said two clutch members when said housing is subjected to forcible lateral pressure.

2. In a guard of the character described, a housing normally surrounding the cutter,

said housing being capable of vertical movement and limited lateral movement, a vertically suspended swingable carrier for said housing, a normally inactive elevator-shaft rotatably mounted in said carrier in axial alignment with the axis of the cutter, said elevator-shaft being screw-threaded, a counterpart screw-threaded element working on said elevator-shaft and connected with said housing whereby, when said elevator-shaft is rotated in one direction the housing is raised on said carrier, a clutch member rotating continuously with the cutter and concentrically with said elevator-shaft, a cooperative clutch member longitudinally slideable on said elevator-shaft but fixed to rotate therewith, and means on said carrier for actuating said second mentioned clutch member to effect the engagement of said two clutch members when said housing is subjected to forcible lateral pressure so as to swing said carrier.

3. In combination with a machine of the character described, having a work-table and a cutter thereon rotating about a vertical axis, a vertically adjustable support on said table, a swingable carrier suspended from said support, a housing vertically movable on said carrier and normally surrounding said cutter, and means for raising said housing comprising a clutch member mounted axially with respect to said cutter and rotatable therewith, said clutch member having a journal bearing therein, said carrier having a journal bearing in its upper portion, an elevator-shaft rotatably supported in said two mentioned journal bearings, and having screw-threads thereon, a counterpart screw-threaded element working on said elevator-shaft and connected to said housing whereby, when said shaft is rotated in one direction said housing is raised, but when said shaft is relieved of power said housing returns to normal position, a clutch member sleeved on said elevator-shaft to slide longitudinally thereon but being fixed to rotate therewith, and means for actuating said clutch member so as to engage said clutch member on said cutter when said housing is subjected to forcible lateral pressure sufficient to swing said carrier on its support.

4. In a guard of the character described, a housing normally surrounding the cutter, said housing being capable of vertical movement and limited lateral movement, means for raising said housing including a normally inactive power element and a normally disengaged power element in co-operative relation to said first mentioned power element, said second mentioned power element operating continuously with the cutter, means for connecting said two mentioned power elements when said housing is subjected to forcible lateral pressure, a yieldable

operative connection between said first mentioned power element and said housing, and an adjustable stop element for limiting the upward travel of said housing and effecting the release of the connection between said housing and said power element.

5. In a guard of the character described, a housing normally surrounding the cutter and being capable of vertical movement and limited lateral movement, a vertically suspended swingable carrier for said housing, a support for said carrier comprising a standard, a horizontal arm feathered on said standard, means for securing said arm in adjusted position, an externally screw-threaded sleeve feathered on said standard below said arm, means for securing said sleeve in adjusted position, and an adjusting member having a counterpart screw-threaded portion working on said sleeve and co-operatively engaging the under side of said arm.

6. The combination with the work-table of a machine of the character herein described, and a cutter on said table rotating about a vertical axis, a standard on said table, a horizontal arm vertically adjustable on said standard, a tubular carrier member swingably suspended from said horizontal arm in substantial axial alignment with the axis of said cutter, a housing vertically slidable on said carrier tube, an annular clutch member mounted axially of the cutter and rotatable therewith, said clutch member having a journal bearing therein, a journal bearing in the upper portion of said carrier tube, a shaft supported at its upper end in said journal bearing in said carrier tube and having its lower end supported in said journal bearing in said clutch member, said shaft having screw threads thereon, a box surrounding said shaft and having a limited slidable connection with said housing, a counterpart screw-threaded element working on said shaft, said element being located within said box and having a releasable interlocking engagement therewith, a spring for yieldably maintaining such engagement and being capable of sustaining the combined weight of said box and said housing when suspended therefrom, an

abutment member on said shaft having an inverted annularly tapered head, a clutch member sleeved on said shaft to move longitudinally thereof but being fixed to rotate therewith, said clutch member having a counterpart tapered head opposed to that of said abutment and a clutching portion in co-operative relation to said first mentioned clutch member, a spring for yieldably holding said second mentioned clutch member against said abutment member and disengaged from said first mentioned clutch member, an annular wedge element supported between said tapered head portions of said abutment and clutch member, said wedge element being loosely fitted on a circular bearing in said carrier tube whereby, when said housing is subjected to forcible lateral pressure to swing said carrier tube on its support the engagement of said two mentioned clutch members is effected.

7. In a guard of the character described, a vertical elevator-shaft having screw threads thereon, a housing support comprising a cylindrical box surrounding said shaft, a cylindrical nut rotatably fitted and longitudinally slidable in said box and working on the screw-threaded portion of said shaft, said nut having an annular flange at its lower end, the under side of said flange being serrated, an annular bushing in said box having serrations on its upper side to co-operate with those on said nut, and a spring interposed between the top wall of said box and said annular flange of said nut.

8. In a guard of the character described, a suspended swingable carrier member, a screw-shaft journalled at its upper end in the upper portion of said carrier member and at its lower end independently of said carrier member, a guard housing vertically movable on said carrier, a box surrounding said screw-shaft and having a limited slidable supporting connection with said housing, a nut working on said screw-shaft within said box and having a spring-pressed releasable interlocking engagement with said box, and a clutch member on said screw-shaft actuated by the swinging of said carrier member.

ROBERT F. PADEN.
